(57) **CLAIM**

The ornamental design for a hose coupling, as shown and described.

DESCRIPTION

FIG. 1 is a perspective view of a hose coupling.

FIG. 2 is a front view of the hose coupling.

FIG. 3 is a back view of the hose coupling.

FIG. 4 is a right side view of the hose coupling.

FIG. 5 is a left side view of the hose coupling.

FIG. 6 is a top view of the hose coupling; and,

FIG. 7 is a bottom view of the hose coupling.
